C. HOFFMAN

DOOR FASTENER

Filed Aug. 11, 1923

FIG. 1.

FIG. 2.

FIG. 3.

Inventor

CARL HOFFMAN

By *Francis P. Maguire*
Attorney

UNITED STATES PATENT OFFICE.

CARL HOFFMAN, OF ALLENTOWN, PENNSYLVANIA.

DOOR FASTENER.

Application filed August 11, 1923. Serial No. 656,852.

To all whom it may concern:

Be it known that I, CARL HOFFMAN, a citizen of the United States, residing at Allentown, in the county of Lehigh and State of Pennsylvania, have invented certain new and useful Improvements in Door Fasteners, and I do hereby declare the following to be a full, clear, and exact description of the invention, such as will enable others skilled in the art to which it appertains to make and use the same.

This invention relates to door fasteners and particularly to improvements in a door fastener adapted for locking a door in either closed or partially open position.

An object of this invention is to provide a keeper and a latch mounted on a door and jamb adapted for locking the door in closed position and provided with operating means for the latch adapted for association with the keeper to lock the door in partially open position.

Another object of the invention is to provide a keeper and latch for an outwardly opening door adapted to lock the door in closed position in which the latch is provided with an operating member adapted for locking cooperation with the keeper for holding the door in partially open position.

The invention further includes the provision of a U-shaped member having one leg pivotally connected with the latch and the other leg adapted for sliding movement through the keeper to guide it into locking cooperation with the keeper for fastening the door in partially open position.

The invention includes other objects and improvements in the details of construction which are particularly pointed out in the following description and claims and shown in the accompanying drawing in which Figure 1 is a perspective view of an outwardly opening door showing my device mounted on the door and jamb and positioned for locking the door partially open. Figure 2 is a horizontal section through the door and jamb showing the invention in plan with the parts in unlocked position and the handle member shown in dotted lines in its position preparatory for the partial opening of the door, and Figure 3 is a horizontal section through the door and jamb showing a plan of the invention with the parts in position to lock the door closed.

1 indicates the jamb and 2 the door open-

ing outwardly therefrom which is provided with a plate 3 rotatably supporting a spindle 4 from which projects the latch 5 adapted for locking cooperation with the keeper 6 mounted on the door jamb. The keeper 6 is formed with a longitudinally extending recess 7 in the body portion thereof and an opening 8 communicating with said recess as shown in Figure 2. The keeper is provided with openings at 9 adapted to receive a locking pin 10 provided with a chain connection 11 secured under one of the attaching screws mounting the keeper on the jamb. A U-shaped member 12 has one of its free ends or legs pivotally mounted in the spindle 4 as indicated at 13 and forms an operating handle for rotating the spindle to engage or disengage the latch from the keeper. The member 12 is adapted for sliding cooperation with the keeper, and the free end being inserted through the opening 8 and thus coupling the member and the keeper. When the door is opened as far as engagement between member 12 and keeper 6 will permit, pin 10 is positioned to prevent disengagement of the member 12 from the keeper thus effectively fastening the door in partially open position. An opening 14 is formed in the spindle 4 to receive the free end of the member 12 when the parts are in unlocked position, as shown in Figure 2, and serves to limit movement of said member toward the door thus obviating any likelihood of the same being scarred.

Figure 3 shows the latch 5 in engagement with the keeper 6 in its position for locking the door in the closed position. By using the member 12 as an operating handle the latch may be rotated from the locked position in Figure 3 to the unlocked position as shown in Figure 2, and upon the movement of the member 12 into the position shown in dotted lines in Figure 2 the parts are ready for the movement of the door into partial open position.

It is to be noted that this invention is particularly adapted for use with doors opening outwardly and includes a single member adapted to act as an operating means for the latch and additionally to cooperate with the keeper for fastening the door in partially open position. When positioned as shown in Figure 1 for maintaining the door ajar, the member 12 effectually maintains the latch 5 in inoperative position.

tion so that no damage will be done to either latch or keeper should the pin 10 be removed and the door slammed shut.

I claim as my invention:

- 5 1. A door fastener including a keeper mounted on the door jamb, a rotatable latch mounted on the door for engagement with the keeper to lock the door in closed position, a member secured to the latch forming an operating handle therefor to engage or disengage the latch from the keeper, and said member having a keeper engaging portion adapted for cooperative engagement with said keeper to lock the door in partly 10 open position when said latch is in ineffective position.
2. A door fastener including a keeper mounted on the door jamb, a latch rotatably mounted on the door, and a member pivotally connected with the latch forming a handle for rotating the latch to engage or disengage it from contact with the keeper to lock the door in closed position, said member further cooperating with the keeper to 15 lock the door in partially open position.
3. A door fastener including a keeper, a latch rotatably mounted on the door for engagement with the keeper to lock the door in closed position, a member pivotally mounted on the latch forming an operating means for the latch and also adapted for sliding engagement with the keeper and means for locking the member to the keeper to fasten the door in partially open position.
4. A door fastener including a keeper having an opening formed therein mounted on the door jamb, a latch mounted on the door adapted for engagement with the keeper to lock the door in closed position, a U-shaped member having one leg pivotally connected to the latch adapted to form an operating means therefor, and having the other leg adapted for sliding movement in the opening in the keeper, and means for locking the member in engagement with the keeper for holding the door in partially open position.
5. A door fastener including a keeper

mounted on the door jamb and formed with a recess extending horizontally therein and an opening communicating with the recess, a latch rotatably mounted on the door for engagement with the keeper to lock the door in closed position, a U-shaped member having one free end pivotally connected to the latch for operating the same, and the other free end adapted for insertion in the recess and opening in the keeper for sliding movement therein limited by the end of the member, and means for closing the open end of the recess in the keeper to lock the member therein for holding the door in partially open position.

6. A door fastener including a keeper mounted on the door jamb, a rotatable spindle carried by the door, a latch carried by said spindle for engagement with the keeper to lock the door in closed position, a pivoted member secured to said latch forming an operating handle therefor to engage or disengage the latch from the keeper, said member having a keeper engaging portion adapted for cooperative engagement therewith to lock the door in partly open position when said latch is in ineffective position, and said latch carrying spindle having means cooperating with said member for limiting movement thereof in the direction of the door when the same is used as a latch operating handle.

7. A door fastener including a keeper mounted on the door jamb, a latch mounted on the door for engagement with the keeper to lock the door in closed position, a pivoted member secured to the latch forming an operating handle therefor to engage or disengage the latch from the keeper being further adapted for cooperative engagement with said keeper to lock the door in partially open position, and means associated with said latch for limiting movement of said member toward the door when used as a latch operating handle.

In testimony whereof I have signed this specification.

CARL HOFFMAN.
